CLAIM

The ornamental design for an electrical connector for electrocardiogram monitoring, as shown and described.

DESCRIPTION

FIG. 1 is a top plan view of the electrical connector for electrocardiogram monitoring; showing our new design;

FIG. 2 is a left side view;

FIG. 3 is a right side view;

FIG. 4 is a front view;

FIG. 5 is a rear view; and

FIG. 6 is a bottom plan view.
